BURCHARD THOENS, OF NEW YORK, N. Y.

EQUALIZING-VALVE.

1,290,803.

Specification of Letters Patent.

Patented Jan. 7, 1919.

Application filed April 13, 1918. Serial No. 228,409.

To all whom it may concern:

Be it known that I, BURCHARD THOENS, a citizen of the United States, and resident of New York, New York county, State of New York, have invented certain new and useful Improvements in Equalizing-Valves, of which the following is a specification.

This invention relates to equalizing valves for use in connection with pumps for handling volatile liquids.

It is well recognized in pumping volatile fluids that considerable trouble is caused from the vapor or gases which are present or given off from the liquids. These gases are the cause of hammering in the operation of the pump and also reduce the volumetric efficiency of the same. It is the object of this invention to provide a valve which will eliminate these defects; to provide such a valve which is of exceedingly simple construction, will operate indefinitely without wear, requires practically no attention and is built so that it can be disassembled quickly and easily.

Other objects and features of the invention will be apparent from the description taken in connection with the drawings, in which—

Figure 1 is an elevation view showing a portion of a pump in section, the liquid receiver connected therewith and illustrating the location of my improved equalizing valve and its connection with the pump cylinder and receiver; and

Fig. 2 is a sectional elevation through the equalizing valve.

Referring to the drawings 10 indicates a receiver which may be supplied with a volatile liquid such as ammonia, hot water or sweet water and syrup from defecating pans, through the pipe 11. The inlet chamber 12 of the pump 13, is supplied with volatile liquid from the receiver by means of the pipe 14. The flow of the fluid from the inlet chamber 12 into the pump cylinder 15 is controlled by means of the valves 16 and 17, the valve 16 being arranged in the valve chamber 18 and the valve 17 being located in the valve chamber 19. The fluid is discharged from the pump cylinder 15 through the discharge valves 20 and 21 into the discharge chamber 22, which is in communication with the discharge pipe 23. The pipe 24 is threaded into the highest portion of the valve chamber 18 and a similar pipe 25 is threaded into the highest portion of

the valve chamber 19. These pipes lead to my improved equalizing valve 26 being connected to the same on opposite sides thereof. The pipe 27 leads from the top of the equalizing valve and is connected to the receiver near the top thereof.

As shown in the drawings the equalizing valve comprises a housing 28 which may be formed with a boss 29 into which the pipe 27 is screwed. The wall of the housing opposite this pipe consists of a removable plate 30 which is formed with the spaced openings 31 and 32. The opening 31 is formed with a valve seat 33 and the opening 32 with a like valve seat 34. The plate 30 in addition to forming a wall for the housing 28 also forms a wall for a second housing 35. This latter housing is provided with a partition 36 which divides the same into two chambers 37 and 38. The pipe 24 is in communication with the chamber 37 and the chamber in turn is in communication with the interior of the housing 28 through the opening 31. The pipe 25 is connected into the chamber 38 and the chamber is in communication with the interior of housing 28 through the opening 32. The two housings and the interposed plate 30 may be securely clamped together by the bolts 39. An arm 40 is arranged within the housing 28 being pivotally mounted on a short shaft 41. Pivoted to one end of this arm is a spindle 42 which has a valve disk 43 threaded on its lower end, said disk being located in the chamber 38. The other end of the arm has a similar spindle 44 pivoted to the same which at its lower end has threaded thereon a valve disk 45 located within the chamber 37. The valve disks 43 and 45 have spherical surfaces which coöperate with the seats 34 and 33 respectively, to close the openings 32 and 31.

In the operation of the device if the piston of the pump is moving toward the left as viewed in Fig. 1 the pressure on the discharge side thereof acting through the pipe 25 will cause the valve to close the opening 32 thus rocking the arm 40 and opening the valve controlling the opening 31. Thus communication is established between the right hand end of the pump as viewed in Fig. 1 and the receiver. This will permit the fluid to flow from the receiver into the said end of the pump, thereby expelling any gas which may be in the cylinder through the pipe 24, equalizing valve and pipe 27 into the top of the receiver. It will be ap-

- parent that in this manner the pump cylinder will be filled with liquid, all of the gases having been expelled so that the pump will operate at a maximum volumetric efficiency 5 and there will be no hammering of the same. When the direction of movement of the piston is reversed a similar operation of the parts occurs in connection with the other end of the cylinder.
- 10 It will be apparent that I have provided a very simple valve which is practically free from wear as there is no sliding movement. The valves are opened and closed by the rocking of arm 40 on the shaft 41 and it is 15 obvious that this rocking movement can go on almost indefinitely before there is any derangement of the valve due to wear. Even if after a long period of operation a looseness should develop, the valve will operate 20 perfectly because of the disks having the spherical surfaces and because they are carried on the pivoted spindles, this construction permitting the valves to always adjust themselves to the seats.
- 25 Although I have described an embodiment of the invention specifically it is apparent that details thereof may be varied to a considerable extent without departing from the spirit of my invention.
- 30 Having thus described my invention what is claimed as new and desired to be secured by Letters Patent is:—
1. An equalizing valve for pumps including a housing having an outlet and two 35 openings each formed with a valve seat, a second housing secured to said first housing

having a partition dividing the same into two chambers, each chamber being in communication with the interior of said first housing through one of the said openings 40 and each chamber also having a connection for a pipe, an arm pivoted in said first housing, each end of the arm having a spindle pivoted thereto which extends through the adjacent opening in the housing, and, a 45 valve disk on the end of each of the spindles within the associated chamber arranged to coöperate with the seat around the corresponding opening.

2. An equalizing valve for pumps including a housing having an outlet and two 50 openings in one wall thereof each formed with a valve seat, a second housing secured to said first housing having a partition dividing the same into two chambers the said wall also forming a wall for the second housing each chamber being in communication with the interior of said first housing through one of the said openings and each chamber also having a connection for a pipe, 55 an arm pivoted in said first housing, each end of the arm having a spindle pivoted thereto which extends through the adjacent opening in the housing, and a valve disk on the end of each of the spindles within 60 the associated chamber arranged to coöperate with the seat around the corresponding opening.

In testimony whereof I affix my signature.

BURCHARD THOENS.
